DRESSING DEVICE FOR GRINDING WHEELS

Michael Hrankowski, Plainfield, N. J.

Application July 14, 1948, Serial No. 38,610

1 Claim. (Cl. 125—11)

1

This invention relates to new and useful improvements in devices for dressing grinding wheels.

The cardinal object of the invention is to provide an improved such device, for dressing or truing the grinding face of a grinding wheel, and which is characterized by marked compactness throughout, yet nevertheless with exceptionally rugged parts, and these last strikingly few in number.

Another object is to provide a device as above, and with only a very few of its few parts relatively movable in using the device, and, further, with these parts so assembled and related that by their very arrangement and special shapings not only are all the parts kept few in number but they are exceedingly easy and inexpensive to fabricate and assemble, and, besides, the advantage is present that should dust and grit be accumulated to an extent possible to become an agent to disturb easy and expeditious manual operation of the device such an accumulation is readily removed without take-down of the assembly.

The above and other objects, and the various other novel features and advantages of the device will be pointed out or become apparent hereinafter.

For further comprehension of the invention, and of the objects and advantages thereof, reference will be had to the following description and accompanying drawings, and to the appended claim in which the various novel features of the invention are more particularly set forth.

In the accompanying drawings forming a material part of this disclosure:

Fig. 1 is a perspective view of a familiar bench and floor type of grinding machine, including the conventional flat guide plate on which the new device may, for instance, be expeditiously and efficiently temporarily mounted for using the device to quickly dress the grinding wheel of said machine.

Fig. 2 is a top perspective view of the new device, detached from said plate or other selected support.

Fig. 3 is a top plan view of said device, partially broken away and partially in section.

Fig. 4 is an end elevation thereof, looking toward the right in Fig. 3.

Fig. 5 is a detail view, being a fragmentary vertical section on the line 5—5 of Fig. 3.

Fig. 6 is a perspective view of that part of the device which will below be called the barrel member, and showing also an integral auxiliary structure incorporating a pair of slides; said member

2

being viewed in substantially the direction of the arrow 6 of Fig. 2.

The device for dressing grinding wheels, according to the present invention, includes a base plate 10 flat all over its bottom and having a main portion of elongate rectangular outline all around except at one corner area where the said plate has a reduced extension 11 the root section 12 of which is curvilinearly extended away from said corner area.

Along the end of said main portion of the plate 10 opposite to the end thereof from which said extension 11 projects, and at the top of the plate, is an integral rib 14. At the inner side of this rib 15 is a gib 15, undercut along its side remote from the rib. At the opposite end of the main portion of the plate 10 is another gib 16, this undercut along its side facing the gib 15.

The gib 16 is fixed on top of the plate 10, as by riveting or in any other suitable way, with the vertical wall of its undercut portion and its vertical wall thereabove in parallelism with the inner side of the rib 14.

The gib 15, having its side adjacent to the rib 14 and also both of its vertical wall portions facing the gib 16 in parallelism with the vertical wall of the said undercut portion of the gib 16, is adjustable toward and away from the gib 16, by means of a pair of set-screws 17 and 18 carried by the rib 14, and this adjustment is locking secured by means of a pair of screws 19 and 20 downwardly entered in countersunk slots 21 and 22 through the gib 15, the lower ends of the shanks of these screws engaging drilled and tapped recesses in the top of the plate 10.

The undercut portions of the gibs 15 and 16 constitute a fixed guideway means relative to a pair of slides 23 and 24, each having a laterally extended bottom flange 23^a or 24^a, for accommodation in said undercut portion of the adjacent gib 15 or 16. These slides 23 and 24 are integral with a cylindrical pocket bearing sleeve or barrel 25; this barrel near opposite ends thereof overlying the slides 23 and 24 near the ends of the latter adjacent to the rear side 26 of the main plate 10. At said ends of the slides 23 and 24, and just beyond the rear side of the barrel 25, the said slides are bridged by a bar-like connector 27 integral with the slides (see Fig. 6) and also integral with the somewhat flattened bottom 28 of the barrel (see Figs. 4 and 5).

The barrel 25 is bored from end to end and such bore is surface finished to perfect cylindricity; and slidable in said bore is a cylindrical member 29 also finished laterally thereof to per-

fect cylindricity, so that easy endwise movement of the member 29 in the barrel 25 back and forth in either direction endwise thereof is provided for when a minutely thin oil film is interposed between the working surfaces of the parts 25 and 29. The barrel 25 at its top and about midway along its length has an aperture 30, through which a drop of oil may be applied for acting as a lubricant; said aperture also serving to afford access to a set-screw 31 to be referred to later.

One end of the member 29 is cut away at top and bottom to provide a reduced integral ear 32, for pivotal connection, as at 33, with one end of a short link 34. The other end of said link is pivotally connected, as at 35, to an end of a lever 36 fulcrumed as at 37 to the outer end of the extension 11 from the main plate 10. The opposite end of said lever carries a handle 38.

By means of said handle, the member 29 may be shifted longitudinally to one limit of its movement relative to the barrel 25, and then to the other limit of its movement relative to said barrel. The amplitude of this reciprocatory movement of the member 29 is determined by the length of a slot 39 along the rear side of the barrel 25. This slot overlies the bar-like connector 27, has rounded ends, and is about as long as said connector.

Through said slot 39 there is projected the 30 holder 40 for the grinding wheel dressing instrumentality.

Said holder is here shown as post-like and having at its outer end a bifurcation as at 41 for rotatively mounting, on a shaft element 42 35 integral with a set-screw 43, a group 44 of stone dressing instrumentalities of a familiar kind incorporating a plurality of alternatively arranged plane and toothed disks.

The inner end portion of the holder 40, where 40 the latter projects through the slot 39, is cylindrical, and this formation is continued as indicated at 45 to the inner end of said holder; this cylindrical portion of the holder for being inserted into a matchingly shaped recess 46 extended into the member 29 transversely thereof (see Fig. 5).

Said recess is about midway along the length of the member 29, and, now again referring to the already mentioned set-screw 31, this is in a drilled and tapped hole vertically above the recess 46. Thus, with the aperture 30 through the top of the barrel 25 located at about midway along the length of said barrel, which aperture it will be noted is quite a bit larger than the head of said set-screw, the set-screw 31 is made readily accessible by way of said aperture when the member 29 is arranged to bring the central portion of its length substantially midway between the opposite ends of the barrel 25.

By way of the set-screw 31, the holder 40 is locked fast to the member 29, for rearward projection therefrom and through the slot 39 as already pointed out. The slot 39 is so proportioned, and so placed on the barrel 25, relative to the length of said barrel and to the length of the member 29, that with the latter at either of its extreme limits of reciprocation the entirety of the bore through the barrel 25 is occupied by some portion of the member 29.

Moreover, the provision on the barrel 25 of the slot 39 and also the aperture 30, makes it almost an instantaneous matter to remove the holder 40 and substitute another type of holder having an inner end portion fittable in the recess 46.

Rigidly upstanding from the main plate 10 is a post 47 having therethrough a drilled and tapped hole near its upper end for taking a feed-screw 48 shown as having a wing-type finger-piece 49 at its outer end. The inner end of this screw bears against the outer side of the barrel 25, with the post so located that such bearing is at a point along the barrel about midway between its ends.

For normally urging the barrel 25 to a position such that the dressing instrumentality 44 is retracted, a retractile spring 50 is connected at one end to a hook 51 secured to the post 47 and at its other end to a hook 52 carried by the connector 27.

The main plate 10 is provided with a pair of slots 53 and 54, whereby bolts or screws may be employed to secure the device on a suitable support, as, for example, on the flat guide plate 55 of the grinding machine shown in Fig. 1; this plate having two tapped holes 56 and 57, in placements agreeing with the locations of the slots 53 and 54 on the said plate 10.

With the device thus mounted, say on the guide plate 55, the dressing instrumentality 44 of the device will be workingly directed toward the grinding wheel 58. By turning of the feed-screw 48, advancement of the barrel 25, and with it said instrumentality 44, is effected, for proper engagement of said instrumentality with the wheel 58; and then, by swinging the handle 38, said instrumentality 44 may be caused to traverse laterally the periphery of the wheel 58. Back and forth swinging of said handle causes the instrumentality 44 to sweep back and forth across the periphery of the wheel while it is in rotation. As the wheel dressing continues, the feed-screw 48 is from time to time, as and if required, further turned. When the wheel dressing is completed, turning of the feed-screw in the opposite direction frees the spring 50 to retract the instrumentality 44 to cause disengagement thereof from the wheel.

The new device, efficiently and easily manually operative as above, is exceptionally compact, and while rugged throughout of very light weight. The only accumulations of dust and grit ever possibly to become a little troublesome are under the gibs 15 and 16, in the aperture 30 and in the slot 39. By arranging the plate 10 substantially vertical with its side 26 lowermost and tapping the device sharply against a fixed anvil or the like, any accumulations of dust and grit under said gibs and in the said slot are ejected. By turning the device upside down, so that the aperture 30 is lowermost, a similar tapping treatment of the device results in any dust and grit accumulation in said aperture being ejected.

While I have illustrated and described the preferred embodiment of my invention, it is to be understood that I do not limit myself to the precise constructions herein disclosed and the right is reserved to all changes and modifications coming within the scope of the invention as defined in the appended claim.

Having thus described my invention, what I claim as new, and desire to secure by United States Letters Patent is:

In a device for dressing a grinding wheel having an elongated base to be mounted adjacent the grinding wheel with its length extended at right angles to the grinding wheel to be dressed and having a slide mounted thereon for movement toward and away from the wheel, an elong-

gated barrel fixedly mounted on the slide parallel to the elongation of the base and formed with an elongated slot in its side, a cylindrical member slidably extended through said barrel and formed intermediate of its ends with a recess aligned with said slot, means connected between the base and said cylindrical member for manually sliding said cylindrical member axially in one direction and then in the other direction relative to said barrel, a dressing tool having an inner end portion passed slidably through said slot and into said recess so that dressing tool will move with said cylindrical member, a set screw threaded through said cylindrical member and abutting the inner end portion of said dressing tool retaining it in position on said cylindrical member, a post extended from the base on the side of said cylindrical member opposite the side from which said dressing tool extends, an adjustment screw threaded through said post and abutting said cylindrical member to be turned relative to said post for moving the

slide and said cylindrical member away from the post, and a contraction spring connected between said post and said slide in a direction in which said cylindrical member is abutted against said adjustment screw.
